UNITED STATES PATENT OFFICE.

LEN A. BANTA, OF CLEARFIELD, PENNSYLVANIA.

REFRIGERATOR SHOW CASE.

Application filed November 17, 1923, Serial No. 675,407. Renewed October 8, 1925.

To all whom it may concern:

Be it known that I, LEN A. BANTA, a citizen of the United States, residing at Clearfield, in the county of Clearfield and State of Pennsylvania, have invented certain new and useful Improvements in Refrigerator Show Cases; and I do hereby declare the following to be a full, clear, and exact description of the invention, such as will enable others skilled in the art to which it appertains to make and use the same.

This invention relates to improvements in refrigerator show cases, and more especially to such cases which are provided with refrigerating means for preserving articles of food positioned within the same, said cases being further provided with means whereby a person in front of the show case may readily see through the front portion and top thereof, said means comprising spaced plates of glass positioned at the front and top of said cases.

An object of the invention is to provide a refrigerator show case with a plurality of spaced ice receiving compartments fixedly attached to doors at the rear of said case whereby when said doors are opened the supply of cracked ice and salt may be readily replenished.

A further object of the invention is to provide a refrigerator show case with spaced plates of glass in the front and top thereof, and with suitable ice receiving compartments or tanks placed along the back of said case in such a manner as to efficiently cool the interior of the said case to preserve the goods therein.

Other objects will appear as the description proceeds.

In the accompanying drawings which form a part of my application,

Fig. 1 is a front elevation of my improved refrigerator show case;

Fig. 2 is a rear elevation of my improved show case;

Fig. 3 is a horizontal longitudinal sectional view through a portion of my show case, and

Fig. 4 is a transverse vertical sectional view through the show case.

Like characters of reference are used throughout the following specification and the accompanying drawings to designate corresponding parts.

The front 1 of my improved refrigerator show case is provided with spaced partitions

2, between which are positioned three spaced plates of glass 3, in such a manner as to provide an air insulation space between the adjacent panes of glass.

Spaced plates of glass 4 are also positioned at the top of the show case in like manner so that there will be air insulation spaces between the said plates to provide for a more perfect insulation to keep the contents of the case cold.

A plurality of small doors 5 are hinged at 6 at the rear of the case 1, and in such a manner as to swing downwardly. Suitable operating handles 7 are attached adjacent 70 the upper portion of the doors 5.

On the inside of each of the doors 5, I have positioned a substantially rectangular shaped ice tank 8 which is fixedly attached thereto by suitable fastening means 9. An 75 opening 10 is formed in the bottom of each of the ice tanks 8 so that the water from the ice may drip down into a shallow pan 11 positioned immediately below the said tanks. A drain pipe 12 is connected to the 80 tank 11, and has its upper end spaced from the bottom thereof, so that there will always be a small amount of ice water in the pan, to assist in the cooling and preserving of the foods in the refrigerator. It will be noticed that the lower ends of the ice tanks 8 extend below the level of the water in the pan 11 and thereby additionally chill or cool the water in the said pan to more efficiently cool the refrigerator.

Suitable walls 13 of galvanized iron surround the tanks 8 in spaced relation therefrom, and serve to assist in the directing of the air from the forward part of the show case down and around the ice tanks 8 and up 95 along the front of the show case again. A bottom tray 14 of galvanized iron is positioned approximately two inches above the ice water receptacle 11 and is provided with a plurality of openings 15 through which 100 cold air is adapted to pass on its upward course through the refrigerator.

A second shelf 16 is positioned in spaced relation with the bottom shelf and is either provided with a plurality of slats 17 or may 105 be made of woven wire if desired, so that the cold air may pass through the same without being obstructed.

Larger doors 18 are positioned between the ice compartment doors 5 and are hinged at 110 19, and are provided with suitable handles 20 whereby the same may be raised and

lowered to place food into the show case or to remove the same therefrom.

A suitable mass of insulating material 21 is adapted to be positioned along the whole length at the bottom of the show case. Suitable supporting legs 22 are provided for holding the case slightly elevated above the level of the floor.

From the foregoing description it will be apparent that the circulation of air will be in a downward direction through and around the ice tanks 8 over the surface of ice water in the pan 11 toward the front of the case, and up through the openings 15 in the bottom shelf 14, and finally through the openings between the slats 17 and up along the top wall of the case and down into the ice tank again.

It will be readily seen and understood that due to the positioning of the spaced plates of glass 3 and 4, a prospective purchaser may readily see the contents or foods within the interior of the show case. The spaced plates of glass not only permit of the viewing of the goods within the case, but also serve to positively and efficiently insulate the case on those sides so that the cold air will be kept within the case.

It will be understood that I do not intend

to limit myself to the exact and specific construction of the invention, as many minor changes in detail of construction may be resorted to without departure from the spirit of the invention.

Having thus described my invention what I claim as new and desire to secure by Letters Patent of the United States is:

A show case refrigerator having transparent panels each composed of a plurality of spaced plates of glass, means for gaining access to the interior of the case for introducing and removing articles to be refrigerated, a plurality of doors hinged to the case by their bottom edges, each door having an ice container secured to the inner face of the door with its bottom below the lower edge of the door, a partition spaced about each ice container when the latter is positioned within the case, said partitions having their upper edges spaced from the top of the case and their lower edges spaced from the bottom of the case, a drip pan extending over the bottom of the case, a perforated shelf for supporting the articles to be refrigerated over the drip pan and a drain pipe for the pan.

In testimony whereof I affix my signature.

LEN A. BANTA.
